UNITED STATES PATENT OFFICE.

NICHOLAS J. DELOH, OF RITCHIE, ILLINOIS.

AUTOMOBILE-DOOR-OPENING DEVICE.

1,338,560.

Specification of Letters Patent. Patented Apr. 27, 1920.

Application filed February 12, 1919. Serial No. 276,729.

To all whom it may concern:

Be it known that I, NICHOLAS J. DELOH, a citizen of the United States, residing at Ritchie, in the county of Will and State of Illinois, have invented certain new and useful Improvements in Automobile-Door-Opening Devices, of which the following is a specification.

The present invention comprehends generally improvements in that class of inventions known as closure operators, more particularly to an automobile door opening device.

This invention has for one of its objects to provide a device of the above mentioned character designed to be associated with the catch of the door of an automobile, preferably taxi-cabs, limousines, or the like, the main operating handle being positioned near the chauffeur who may open the door to receive or discharge passengers without leaving his seat, while at the same time the door may be opened by the passenger in the usual manner, the component parts of the mechanism being so related that the main operating handle will be inactive when the door holding mechanism is manually actuated.

Another object of the invention is to provide a device of the above mentioned character wherein clutch means of novel construction forms a part of the operating mechanism and normally arranged in inactive position to permit a person to open the door without moving the main operating mechanism, while at the same time the clutch means is movable into coactive relation with the remaining parts of the mechanism to permit the chauffeur or driver to open or close the door without leaving his seat.

The invention is clearly illustrated in the accompanying drawings, in which—

Figure 1 is a top plan view of the improved door opening device applied to an automobile, a portion of which only is shown.

Fig. 2 is a side elevation showing the device applied, the door being shown in closed position.

Fig. 3 is an enlarged transverse sectional detail taken on line 3-3 of Fig. 1.

Fig. 4 is an enlarged fragmentary detail, partly in section, showing the connection of the stationary arm and the loose arm with the rocker shaft or rod,

Fig. 5 is an enlarged top plan detail of a portion of the operable connection between the rod or shaft and the catch means, the door being shown in horizontal section,

Fig. 6 is a top plan detail of the catch, 60

Fig. 7 is a bottom plan view of the parts shown in Fig. 6,

Fig. 8 is a perspective detail view of portions of the operating rods and levers.

Similar characters of reference are employed in all of the above described views, to indicate corresponding parts.

In the drawings a portion of an automobile is shown constructed along the lines of a limousine or taxi-cab, the body or cab 70 portion 1 of which is provided with rear hinged doors 2, only one of which is shown, while mounted on the body and operable from a point near the driver's seat and associated with the doors, is the improved door 75 opening mechanism.

The catch means which normally holds the door closed consists of a casing 3 attached near the free edge of the door, while slidably therein is a latch bolt 4 operating 80 within a keeper 5 on the casing 3, and held yieldably supported in projected position by suitable resilient means such as a coiled contractile spring 6, the ends of which are secured respectively to the keeper and to a 85 bar 25 connected in vertical position to the inner projecting end of the latch bolt. In order to open the door in the customary manner a shank 8 is journaled through both walls of the door and has projecting therefrom a bifurcated bar 9 which is operably arranged about the lower projecting end of a vertical arm 25 as shown. The knobs, designated 8', on the respective ends of the shank 8, enable the latter to be turned from 90 either side of the door by a person desiring to enter or leave the cab.

In order to operate the latch from a point near the chauffeur's seat, a vertical shaft or rod 11 is journaled in horizontal bearings 12 100 carried by the body of the vehicle and has extending from the upper end a lateral arm 13, the inner end of which is preferably keyed to the shaft while the outer end has operably connected thereto one end of a link 105 14. A bracket 15 is mounted on the door 2, being formed with a central opening which is arranged in registration with an opening in the front wall of the door, the latter being preferably hollow, and this bracket is 110

formed with laterally extending spaced horizontal ears 16 preferably positioned near the upper and lower edges of the opening in the bracket, while swingingly mounted for horizontal movement between the ears, preferably at a point medially of its ends, is an arm 17 to the outer end of which the opposite end of the link 14 is pivoted. The inner portion 18 of the arm 17 is positioned 5 between the inner and outer walls of the door 2 and is free to swing forwardly to a limited extent owing to a laterally extending lug 19 which is integral with one side thereof and designed to contact with the 10 outer wall of the door 2 when the member 17 has been moved a certain predetermined distance, for a purpose that will presently appear, while movement in the opposite direction is also limited by another lateral lug 20 which extends oppositely to the lug 19 and prevents forward movement of the arm 17 beyond a certain point, the construction being apparent by reference to Fig. 5. A lever 21 is swingingly mounted by means of 15 a pintle 22 relative to the inner wall of the door 2 the lower end of the lever lying in proximity to the inner portion 18 of the horizontally swinging arms 17, while the upper portion of the lever 21 has connected thereto one end of a connecting rod 23, the opposite end of which is operably connected as 20 to 24 to the upper portion of the bar 25. By this construction a person desiring to enter or leave the cab grasps either of the 25 knobs on the shank 8 for rotating or rocking the shank so that the bifurcated bar which is operably arranged about the depending portion 10 of the bar 25 retracts the latch bolt 4 against the tension of the 30 spring 6. This action moves the connecting bar 23 rearwardly, causing the lower portion of the lever 21 to swing forwardly but will not act against the portion 18 of the lever 17. The manually operable mechanism which 35 is positioned near the front seat to be conveniently manipulated by the chauffeur, consists of a transverse shaft 26 journaled in bearings 27 and has rising therefrom a handle lever 28. An arm 29 is carried by the 40 shaft and depends therefrom and extends in a direction opposite to the substantially vertically disposed lever 28, while the lower end of the arm has connected thereto one end of a connecting bar 30 the opposite end of 45 which is operatively associated with improved mechanism designed to coact with a vertical shaft 11, when the handle lever 28 is moved forwardly, to swing the arm 13 connected to the shaft, as well as the lever 50 17, which is connected with the arm 13, rearwardly causing the inner portion of the lever 17 to move forwardly to act against the lever 21 for the retracting of the catch bolt 4, the lug 19 engaging the outer wall of 55 the door immediately subsequent to the

swinging of the lever or arm 21, to limit the movement of the lever 17 and thus exert a pull on the door for the opening thereof.

The mechanism between the rod 30 and the shaft 11 consists of an arm 32 the inner 70 end of which is keyed to the lower projecting end of the shaft 11, another arm 33 having its inner end bifurcated and loosely arranged about the shaft 11 so that the bifurcated portions 34 are positioned above 75 and below the keyed inner end of the shaft 11 as shown in Fig. 4, while the outer end of the arm 33 is connected as at 35 to the rear end of the connecting rod 30. The forward face of the arm 33 is positioned normally in juxtaposed relation with the face of the arm 32 so that when pulled forwardly, owing to the contacting relation with the arm 32 which is rigid upon the shaft 11, a rotation of the shaft 11 is effected 80 for the operation of the catch mechanism. An automatically operable clutch or catch, generally designated by the numeral 36, is pivoted intermediate its ends at 38 on the bar 33 for coacting with the bar 32, being normally disengaged from the latter but adapted to engage the bar 32 upon the forward swinging of the bar 33, to insure the closing of the door when the handle lever 28 is moved rearwardly. This catch or 85 clutch 36 is designed to be automatically disengaged from the bar 32 immediately preparatory to the final closing movement of the door, so that either one of the knobs 90 may be engaged for rotating the shank 8 for subsequent opening of the door or closing of the same without moving the chauffeur's operating mechanism from a set position. The member 36 is enlarged medially 95 of its ends and provided with transverse 100 openings 37 therethrough for the disposition of the member 36 about the bar 33, while suitable means such as a pin 38, passes through the enlargement and also through the bar for pivotally connecting the member 105 to the bar. A lip 39 is formed on one edge of the clutch member 36 and designed to coact with the adjacent beveled end 40 of the bar 32, and for automatically controlling 110 the position of the member 36, contractile 115 coiled springs 41 are employed and connected to the respective ends of the member 36, while the opposite ends of the springs are connected to a tension controlling element 120 designated as a whole by the numeral 42. This element 42 is constructed in T-shaped 125 form and includes a shank 43, extending from the member 42 intermediate its ends. The springs 41 are connected to the outer ends of the member 42 the latter being pivoted at 45 at the point of juncture of the shank therewith to the bar 33, preferably between the point of connection of the bar and the door. The inner portion of the shank 43 is enlarged in rectangular form 130

and formed with a transverse slot 46, the slot operating about a pin 47, the inner end of which in turn is anchored in the under surface of the body 1 and depends therefrom, while coacting with the pin 47 are 5 adjustable screws 48 mounted through the end portions of the enlargement so as to be positioned at the opposite ends of the slot 46 as indicated, for limiting the movement of the arm 33. By this arrangement, when the arm 33 is moved forwardly at the time the door is being opened, the element 43 being pivoted to the bar and also operably associated with the pin 47, turns about the pin 45 so as to put tension into the spring 41 which is connected with the lip end 39 and releasing the tension in the other spring 41, and when the door has been fully opened the lip 39 will be drawn over the free end 20 of the bar 32, so that when the door is being closed by the movement of the handle lever 28 the lip 39 will cause the arm 32 to swing rearwardly with the arm 33, thereby insuring the closing of the door. The pin 47 25 is mounted on the body of the vehicle and acts on the part 43 to swing the clutch 36 into engagement with the arm "32" as the arm "33" is moved forwardly. Coacting with the member 36 and the springs 41 is a 30 swinging member 49 which is pivoted for horizontal swinging movement to a lateral extension 50 near the end of the bar 33, the member 49 being formed with spaced shoulders 51 and 52, so that when member 49 is 35 arranged in the restricted portion of the opening 37 of the member 33, the shoulders 51 and 52 will coact with the adjacent edge of the member 36. As shown in Fig. 1, the normal position of the member 49 is such 40 that its shoulder 52 is engaged with the clutch member 36 and held in such position by means of a leaf spring 53 carried by the adjacent face of the bar 33, the adjacent spring 41 being then under tension. When 45 the bar 33 is moved forwardly the tension of the spring 41 on the lip end 39 overcomes the tension of the other spring 41, so that the catch member 36 will be rocked about its pivot to a slight extent so that the spring 53 50 acting against the member 49 causes its shoulder 51 to be engaged with the catch member 36, consequently holding the lip 39 in engagement with the bar 32 during the outward swinging movement of the door 55 and during the time the door is open, and also during practically the entire closing movement of the door. During the slight final closing movement of the door and subsequent to the return of the control member 60 42 to its normal position, at which position the spring 41 to the left in Fig. 1 overcomes the tension of the spring 41 on the lip 39, the member 49 will strike the stop 54 which is adjustably mounted in a bracket 55 which 65 depends from the body 1. This action moves the shoulder 51 out of engagement with the catch member 36 so that the adjacent spring 41 will act to swing the catch member 36 until its movement is limited by the engagement of the outer shoulder 52 on the member 49 with the catch member 36, thus normally maintaining the clutch member 36 out of engagement with the bar 32 and permitting the opening of the door by a person desiring to enter or leave the car without operating the lever 28. It is apparent, however, by this arrangement, that when the lever 28 is operated the automatically operable catch member 36 will engage the arm 32 to insure a simultaneous movement of the 70 arms 32, 33 and 13 as well as the bolt retracting member which is operably connected therewith, during the opening and closing movement of the door.

In order to prevent the latch bolt 4 from assuming extending position when the door is in an open position, suitable retaining means is associated with the keeper 5 consisting of a bowed leaf spring 56 having its inner end connected with the keeper 5 and 75 its outer end terminating in a lip 57 designed to engage the outer end of the latch bolt 4 when retracted at the time the door is open. A trip 58 is connected to the outer face of the spring member 56 and projects 80 beyond the lip, being designed to act against the body of the car near the door opening when the door is being moved to a closed position so as to detach the lip 57 of the spring 56 from engagement with the catch 85 bolt 4, and release the latter and permit it to be moved into locking or closed position by the reaction of the spring 6.

The preferred embodiment of the invention is disclosed in the drawings and set 90 forth in the specification, but it will be understood that any modification within the scope of the claims may be made in the construction without departing from the principle of the invention or sacrificing any of 95 its advantages.

Having thus fully described the invention, what is claimed as new and desired to be secured by Letters Patent, is:—

1. The combination with a swinging door 100 having a spring controlled latch bolt for releasably holding the door closed, of an arm 105 swingingly mounted on the door and having oppositely directed stops to limit the movement in both directions, connecting means between said arm and latch bolt, and manually operable means for actuating said arm, whereby the latch bolt is first released and the door then moved into open position.

2. The combination with a body having a 110 doorway opening and a swinging door, of a spring controlled latch bolt for releasably holding the door closed, means for retracting said latch bolt and swinging the door 115 toward open position, a resilient member at-

tached relatively to said door and including a laterally directed terminal adapted to engage the bolt and hold it in retracted position while the door is open, and means carried by the resilient member adapted to be engaged by the body adjacent the doorway opening to disengage the resilient member from the latch bolt and release the same when the door is closed.

10 3. The combination with a swinging rear door of a motor vehicle slidably and resiliently mounted catch means for releasably holding the door closed, of manually operable means on the door for releasing the 15 catch means for opening the door, vertical shafts journaled on the body of the vehicle operably connected with the door and the catch means so that when the shaft is rocked the catch means will be released and the 20 door swung open, manually operable actuating means mounted near the front seat of the vehicle and on the vehicle body, a connecting rod associated therewith and an operable connection between the rod and the 25 shaft, said connecting means including an arm rigid with the shaft, another arm loose on the shaft but connected with the connection rod and spring tensioned automatically adjustable clutch means on the loose arm 30 and positioned so as to permit of the swinging of the rigid arm and the actuating means on the door is operated but is movable to engage the rigid arm upon the operation of the last mentioned actuating means near the 35 front seat of the vehicle.

4. The combination with a swinging rear door of an automobile and slidably and resiliently mounted catch means for releasably holding the door closed, of manually operable 40 actuating means on the door associated with the catch means for actuating the catch means for the opening of the door, vertically disposed shafts operably mounted on the auto-

mobile, an operable connection between the shaft and the door and manually operable 45 actuating means mounted near the front seat of the automobile and operably connected with the shaft for rocking the shaft so as to release the catch means and open the door but being normally arranged in a position 50 so as to be inactive when the first mentioned actuating means is operated for opening the door.

5. The combination with a swinging rear door of a motor vehicle, slidably and resiliently mounted catch means for releasably holding the door closed, of an arm connected to the catch means, a lever mounted in the door and operably connected with the arm, a horizontally swinging arm mounted 60 in the door, a vertically disposed rockably mounted shaft on the vehicle operably connected with the arm, a rigid arm projecting from the shaft, manually operable means on the door and associated with the arm on the 65 catch means for actuating the catch means in opening the door, and other manually operating means on the vehicle consisting of an actuating lever near the front seat of the vehicle, a connecting rod associated therewith, 70 another arm having its inner end loosely arranged about the shaft and the outer end associated with the connecting rod, spring tensioned automatically controlled means on the loose arm movable to engage the adjacent rigid arm when the last mentioned actuating lever is operated for opening the door but normally disengaged from the rigid arm to permit of the operation of the first mentioned actuating means without 75 moving the last mentioned actuating means from a set position.

In testimony whereof, I affix my signature hereto.

NICHOLAS J. DELOHI.
